UNITED STATES PATENT OFFICE.

ROBERT VON MALKOWSKY, OF NEW YORK, N. Y.

VELOCIPED.

SPECIFICATION forming part of Letters Patent No. 310,548, dated January 6, 1885.

Application filed August 30, 1884. (No model.)

To all whom it may concern:

Be it known that I, ROBERT VON MALKOWSKY, of the city, county, and State of New York, have invented certain new and useful 5 Improvements in Velocipedes, of which the following is a specification.

This invention has reference to certain improvements in velocipedes, whereby the working of the same is facilitated; and the invention 10 consists of closed expansible bellows supported on fixed brackets of the upright fork of the velocipede, said bellows being connected by fork-shaped pedal-rods with a transverse balance-rod in front of the seat. The pedals 15 are arranged in the forked parts of the pedal-rods, which rods are provided with forwardly-curved arms that engage cranks on the axle of the driving-wheel. The reciprocating action 20 of the forked pedal-rods and bellows causes the alternating engagement of the cranks of the driving-wheel, so as to impart rotary motion to the same.

In the accompanying drawings, Figure 1 represents a side elevation, and Fig. 2 a front 25 view, of my improved velocipede.

Similar letters of reference indicate corresponding parts.

A in the drawings represents the main or driving wheel, and B the hind or guiding 30 wheel, of my improved velocipede.

C is a yoke or fork that carries at the upper end the steering-handles D, and at the lower end the bearings for the axle of the driving-wheel A.

35 From the lower ends of the fork C extend, in downwardly or backwardly direction, fixed brackets C', to which are applied closed expansible bellows D, of oblong shape, one at each side of the driving-wheel A. The top 40 plates of the bellows E are connected to the brackets C', while the bottom plates are attached to the lower forked ends, E', of the pedal-rods E E. The fork-shaped ends E' are guided in sleeves e of the brackets C'. The 45 fork-shaped ends E' of the rods E are provided with transverse pedals or foot-rests E' at such a distance above the bellows that they do not interfere with the same. The upper slotted ends of the pedal-rods E E are connected

5 to an oscillating balance-rod, F, that is connected in a suitable manner to the spring-arm F, on which the saddle G is supported.

From the lower part of each fork-shaped end E' of the pedal-rod E extends in forward direction an arm, E'', which engages a crank-arm, f, on the axle of the driving-wheel A. The arms E act alternately on the crank-arms f of the arms, and impart thereby rotary motion to the same and the driving-wheel. The lowering of one pedal-rod E produces the 6 expansion of the bellows D, connected thereto, at one side, and simultaneously the lifting of the pedal-rod E at the other side of the driving-wheel, which lifting action is assisted by the contraction of the bellows connected to 6 the rising pedal-rod, said contraction being accelerated by the atmospheric pressure on the bellows. By lowering the raised pedal-rod its bellows is expanded and the other pedal-rod lifted and its bellows contracted, and so on for 7 each stroke of the pedal-rods. The alternating motion of the pedal-rods actuates, by the forward-extending arms E'', the cranks f, and imparts thereby rotary motion of the spindle and driver. The bellows facilitate the working 7: of the velocipede, as thereby the pedals can be arranged nearer to the vertical line passing through the center of gravity of the rider.

Having thus described my invention, I claim 80 as new and desire to secure by Letters Patent—

The combination, in a velocipede, with the driving-wheel, of closed bellows supported on fixed brackets of the fork, forked pedal-rods connected at the lower end of the bottom of 8: the bellows, and at the upper end to a transverse oscillating balance-rod, said forks being provided with forward-extending arms that engage fixed cranks on the axle of the driving-wheel, so as to impart rotary motion to 90 the same, substantially as set forth.

In testimony that I claim the foregoing as my invention I have signed my name in presence of two subscribing witnesses.

ROBERT VON MALKOWSKY.
